[57] CLAIM

The ornamental design for a cleated sole for a sport shoe, as shown and described.

DESCRIPTION

FIG. 1 is a bottom perspective view of a cleated sole for a sport shoe showing my new design;

FIG. 2 is a left side elevational view;

FIG. 3 is a right side elevational view;

FIG. 4 is a front elevational view;

FIG. 5 is a rear elevational view;

FIG. 6 is a bottom plan view; and

FIG. 7 is a top plan view.

The broken line showing of a sport shoe upper is for illustrative purposes only and forms no part of the claimed design.
